UNITED STATES PATENT OFFICE.

DAVID E. GRAY, OF CORNING, NEW YORK, ASSIGNOR TO CORNING GLASS WORKS, OF CORNING, NEW YORK, A CORPORATION OF NEW YORK.

APPARATUS FOR HEAT TREATMENT OF ARTICLES.

1,372,420.

Specification of Letters Patent. Patented Mar. 22, 1921.

Application filed January 8, 1920. Serial No. 350,210.

To all whom it may concern:

Be it known that I, DAVID E. GRAY, a citizen of the United States of America, and a resident of Corning, in the county of Steuben, State of New York, have invented certain new and useful Improvements in Apparatus for Heat Treatment of Articles, of which the following is a specification.

This invention has for its purpose to provide a novel apparatus for feeding articles during the heat treatment thereof, to the end that all parts of the surface of such articles shall be uniformly exposed during the period in question.

This invention comprises the use of a conoidal chamber, rotating about the conoidal axis, and means for controlling the temperature in the interior thereof, preferably, but not necessarily, by conduction through the walls of the chamber. If articles which are circular or substantially circular in cross-section, are fed into one end of such a chamber, gravity will tend in the rotation thereof to cause them to rest on and remain in the bottom thereof, and in this tendency will cause a rotary motion to be imparted thereto, whereby they will roll on the inner wall of such chamber, the articles tending to assume a position at an angle to the plane in which the articles are rotated by the chamber. According to this invention the shape of the articles should be so related to the shape of the chamber that, in the rotation of the articles around their longitudinal axes, they will be given a progressive motion through the chamber. This will be accomplished, with a conoidal chamber, if the articles be non-homologous thereto. For instance, if the articles are cylindrical, they will be given a progressive motion toward the base of conoid, formed by the chamber. Thus this invention in causing a feeding motion due to the rotation of the articles under the influence of gravity and of the rotation of the chamber, dispenses with the use of articulated carrying or driving elements within the chamber, the driving element in this invention taking the form of the rotating chamber.

Referring to the accompanying drawings,

which represent an apparatus embodying the present invention,—

Figure 1 is a side elevation partly in section of such apparatus, shown embodied in a leer. 55

Fig. 2 is a vertical longitudinal section through the conoidal chamber showing the mounting thereof.

Figs. 3 to 8 are diagrammatic views illustrating the principle of this invention, Figs. 60 3, 4 and 5 representing a position of rest toward which a cylindrical article tends in a rotating conoid when viewed from the top, side and end, respectively, and Figs. 6, 7 and 8 representing a position assumed by such a 65 body under the influence of the rotating force of the conoid.

In Figs. 1 and 2, this invention is shown in a form which has been found well adapted to the annealing of glass articles, such as 70 sections of glass gage-tubing, and is embodied in a leer, with proper devices for feeding the tubing thereto, and the following description of construction and operation is directed to such embodiment, as the 75 same forms an example of that species of the invention which contemplates the feeding of a cylindrical-shaped article through a rotating conoidal chamber, although it will be understood that by the specific illustration 80 and description here to be made it is not intended to restrict the invention to annealing of gage-tubing, or to the details of the apparatus described as suitable therefor, such particular description being made for the 85 purposes of illustration, and not as a limitation of the invention.

The structure shown in Figs. 1 and 2, embodies a metallic hollow conoidal body 10, which forms the heating chamber, and is 90 mounted in suitable end bearings 11, formed of lower members 12, supporting the body by means of rollers 13, and of hold down collars 14, the body having flanges 15 thereon to prevent endwise motion. 95 Throughout a greater portion of its length the body is within a chamber 16, preferably lined with heat-insulation 17, and provided with the burners 18 by which it may be heated, and by which its tempera- 100

ture at various points throughout its length may be regulated. The body 10 carries on one end a sprocket wheel 20 driven by a chain 21 from a motor 22 through a reduction gearing 23, the motor being mounted in the base of the frame. An inclined trough 30 is adapted to feed the articles to the entrance (i. e., the smaller) end of the chamber 10, and a second trough 31 is provided 10 into which the articles may drop from the delivery (i. e., the larger) end of the chamber, and be carried to any desired point.

In the operation of the device described, the rotary chamber 10 having been put in 15 rotation, and the flames of the burners 18 having been properly adjusted to give the desired temperatures throughout the different zones of the leer, the articles are fed to the chute 30 down which they slide by gravity into and on the bottom of the smaller end 20 of the chamber 10, substantially lengthwise thereof, in which position the axes of the articles are in the same vertical plane as the axis of rotation of the chamber, which may 25 be called the vertical fore and aft plane. Gravity tends to maintain the articles in this position, while the rotation of the chamber tends to move the articles sidewise and upward. These two forces, acting in opposition 30 to each other, put the articles into variation of rotation around, or substantially around, the longitudinal axes thereof, and cause a slight shifting of the axis of each 35 of the articles from time to time to a position slightly inclined to the fore and aft plane, with the result that in practice some of the force causing rotation of the chamber will be so exerted on the article as to cause rotation thereof substantially on its longitudinal 40 axis and thus a motion of the latter along the chamber. Upon reaching the exit end of the chamber, the article will fall upon the removing trough 31.

It will be further seen, as the motion of 45 the articles is dependent on their rotation, that no part of any articles can remain in prolonged contact with the wall of the chamber, and that the points of contact are constantly shifting. As a result every part 50 of each article will be subjected to the air temperature within the chamber and thus uniform heat treatment is assured.

Figs. 3 to 8 inclusive represent diagrammatically successive positions of a cylindrical article being fed through a conoidal chamber, toward which position it tends as a result of gravity, and which it assumes as a result of rotation of the conoid.

In Figs. 3, 4 and 5, the article 35 is shown 60 in the position of rest toward which it naturally tends, that is to say, resting on the bottom of the conoidal chamber, with which it contacts along the line X—Y, which line, together with the axis D—D of the article,

is in the vertical fore and aft plane in which 65 is the axis E—E of the conoidal chamber, the two axes being, however, at an angle to each other in such plane. If the chamber 10 is now rotated in the direction of the arrow of Fig. 5, the article is, due to the 70 restraining influence of gravity, rotated around its own axis D—D through an angle α . Assuming that C is the circumference of the article (it being the same at both ends), the resultant movement of the points X and 75 Y will be

$$\frac{\alpha}{360} C.$$

If the inner peripheral measurement of the 80 conoid be C' at X and C^2 at Y, the rotation of the conoid and of the article will have shifted the line of contact between the two, so that it now passes through the points X' and Y' at the same distances from X and Y, 85 the angles XOX' and YOY' (O in each case being on the axis E—E) being to each other inversely as C' and C^2 . The axis of the article will thus be inclined to the fore and aft plane of the conoid and as a result of the 90 rotational movement of the walls of the conoid its forward end will be more removed from such plane in the direction of rotation of the chamber than its rear end, as shown in Figs. 6, 7 and 8. At some point in 95 this movement, the article will slip in respect to the walls of the conoidal to again assume the general position toward which it tends as shown in Figs. 3, 4 and 5, but in a position slightly more in advance of that 100 there shown, as is indicated in dotted line in Fig. 6.

It will be further seen, as the progressive motion of the articles is dependent on their 105 rotation, that no part of any article can remain in prolonged contact with the wall of the chamber, and that the points of contact are constantly shifting. As a result of this every part of the article will be subjected to the air temperatures within the chamber, 110 and thus will be uniformly heat-treated. The axis of the conoidal chamber may be horizontal or inclined to the horizontal within limits, with either end up, without departing from this invention, as the propulsive force within the chamber will be sufficient, if the proportions are properly selected, to cause the articles to move even against gravity. The line formed by the intersection of the lower inner surface of the 115 conoid by the fore and aft plane, should, however, be at a less angle to the horizontal than the angle of repose of the article on such surface; as otherwise the article in feeding through the conoid will get beyond 120 control.

By properly selecting the angle of the conoid, the speed of rotation thereof, and

the inclination of its lower surface with the horizontal, the speed of the article in its progression through the chamber, and thus its period of heat treatment, may be controlled. It is obvious that the length of the article treated should be in such proportion to its diameter, and to the diameter of the conoid, that the article will always tend to assume a position of rest with its axis in 10 the fore and aft plane of the conoid.

It is further obvious, while this invention has been specifically shown in connection with means for heating the interior of the chamber, that it is independent of the presence of such heating means. For instance, 15 the conoidal chamber can be used for feeding articles through a cold atmosphere where it is desired to uniformly chill them.

Having thus described the invention what 20 is claimed is:—

1. In a device for the heat treatment of articles, the combination of a hollow conoidal body having its axis of rotation so positioned that the line formed by the cutting 25 of its lower inner face by the vertical

plane containing such axis is at an angle to the horizontal less than the angle of repose of the article to be treated on such surface, and means for controlling the temperature within such body. 30

2. In a device for the heat treatment of articles which in cross-section are approximately circular, the combination of a conoidal rotating chamber whose axis is so positioned that the line formed by cutting 35 its lower inner face by the vertical plane containing such axis, is at an angle to the horizontal less than the angle of repose of the article to be treated on such surface, the diameter of the chamber being such in relation to the article to be treated therein 40 that the article under gravity tends to assume a position with its axis in the vertical plane of the axis of rotation of the chamber, and means for controlling the temperature within such chamber. 45

In testimony whereof I hereunto sign my name this fifth day of January, 1920.

DAVID E. GRAY.
